SHOE BOTTOM UNIT AND METHOD OF
MAKING THE SAME

John M. Whelton, Peabody, Mass., assignor to
United Shoe Machinery Corporation, Paterson,
N. J., a corporation of New Jersey

Application May 21, 1936, Serial No. 81,055

6 Claims. (Cl. 12—146)

This invention relates to improvements in shoe bottom units and to improvements in methods of making shoe bottom units. The present application is in part a continuation of my earlier application Serial No. 600,921, filed March 24, 1932, upon which United States Letters Patent No. 2,065,463 was granted December 22, 1936.

The present invention provides an improved shoe bottom unit which is particularly adapted for use in the manufacture of shoes the uppers of which are to be permanently secured in overlusted position by means of cement and are also to be stapled or otherwise temporarily secured to the shoe bottoms to hold them in place while the cement is setting. As herein illustrated, the improved shoe bottom unit comprises a relatively flexible insole having a lasting lip extending along the lower side of its shank and forepart to which the overlusted margin of a shoe upper may be temporarily secured, and having a portion of the insole material exposed at the outer side of the lip to constitute a lasting surface adapted to receive cement for permanently securing the upper directly to the insole, a relatively stiff reinforcing piece which is secured by means of cement to the upper side of the heel and shank portion of the insole, and a narrow metallic shank stiffener which is located between the insole and the reinforcing piece. The arrangement of the reinforcing piece and the shank stiffener, both at the upper side of the insole, insures that neither will interfere with the securing of an effective cement bond between the overlusted upper margins and the material of the insole. The lasting lip may be formed integrally with the substance of the insole or advantageously the lip may consist of a tape or a plurality of tapes which may be stitched or otherwise secured to the lower or lasting side of the insole. Preferably the tape is stitched flat against the insole so that it will not interfere with a molding operation which is subsequently to be performed upon the insole and the reinforcing piece and as a result of which those parts are to be secured together and arched both longitudinally and transversely to adapt the insole unit to conform to the contour of the bottom of a last. Preferably, also, the tape is stitched to the insole before the reinforcing piece and the shank stiffener are assembled therewith, this practice permitting the tape to be located nearer to the longitudinal center of the insole in the shank portion than it could be if the metallic shank stiffener were present when the stitching took place and thus enabling insole units to be made with exceptionally narrow shank portions as re-

quired in the manufacture of so-called fiddle shank shoes. Moreover, it enables the stitching of the tapes to be more easily accomplished and results in the provision of an insole unit in which no stitches are exposed to view upon its upper side so that the use of a sock lining may be dispensed with if desired.

The invention will now be explained with reference to the accompanying drawing, in which

Fig. 1 is a perspective view of one form of my improved insole unit showing the upper side of the unit;

Fig. 2 is a perspective view of the insole unit showing the lower side thereof;

Fig. 3 is a fragmentary cross-sectional view of the insole member of the unit illustrating the manner in which the lasting lip is formed;

Fig. 4 is a sectional view taken along the line IV—IV of Fig. 2;

Fig. 5 is a longitudinal sectional view of a modified form of insole unit;

Fig. 6 is a sectional view taken along the line VI—VI of Fig. 5;

Fig. 7 is a sectional view similar to Fig. 5 but disclosing a further modified construction;

Fig. 8 is a bottom plan view of the insole unit shown in Fig. 7;

Fig. 9 is a cross-sectional view of a portion of the insole unit shown in Fig. 7;

Fig. 10 is a view similar to Fig. 9 but showing the lasting lip in upstanding position; and

Fig. 11 is a cross-sectional view taken along the line XI—XI of Fig. 8.

Referring first to Figs. 1, 2 and 4 of the drawing, the improved shoe bottom unit or reinforced insole 30 therein shown comprises a relatively flexible insole member 32, a relatively stiff reinforcing member or heel and shank piece 34, and a metallic shank stiffener 36. The insole member 32 may be made of leather or any suitable flexible insole material and died out or rounded to the contour of a full length insole. The heel and shank piece 34 is composed of stiff but readily moldable material, for example, fiber or leather-board, and is shaped to conform in edge contour to the heel and shank portion of the insole. As shown, the heel and shank piece 34 is skived to a thin edge at its forward end so that no undesirable ridge will be produced where it adjoins the insole. The shank stiffener 36 consists of a narrow strip of resilient metal which is initially curved longitudinally to correspond to the longitudinal curvature of the bottom of the last to be used in making the shoe in which the insole unit is to be incorporated. the shank stiffener 36 in assembled relation with the other members of the insole unit two apertures 50 are formed in the insole 32 in positions to receive the opposite end portions of the shank 5 stiffener 36.

In order that the margin of a shoe upper may be temporarily secured to the insole so that the upper will be held in place during the setting of the cement by means of which it is to be permanently attached to the insole, the latter is provided with a lasting lip 38 which, in the case of a leather insole as shown in Figs. 2 and 4, may advantageously be formed integrally with the insole at the flesh side thereof. The lip 38 may be formed by edge slitting or channeling the insole in a well-known manner, as indicated in Fig. 3, to provide an edge slit 40, a channel or edge flap 42, and a feather 44, and subsequently raising or turning the channel or edge flap 42 into an appropriate position (as indicated by full lines in Fig. 2 and by dotted lines in Fig. 3) to constitute the lasting lip 38. Advantageously, the flap 42 will be trimmed, as indicated at 46, the trimming being effected preferably during the channeling operation by means of a suitable trimming tool. As a result of the channeling operation there is formed at the upper side of the feather 44 a lasting surface which is of a character particularly well adapted to receive the lasting cement in such a way as to facilitate the formation of a secure cement bond between the upper and the insole. Preferably the flap 42 will not be raised or turned until after the several parts of the insole unit have been assembled 30 and secured together so that there will be no upstanding flap or lip upon the insole to interfere with the performance of the assembling and securing operation and particularly with the molding operation by means of which the insole unit is ultimately to be shaped to adapt it to fit the bottom of a last. Moreover, since the flap is not upstanding when the molding takes place it will not be distorted or mutilated by the molding pressure.

Prior to the assembly of the parts of the insole unit, the heel and shank portion of the upper surface of the insole and the lower side of the heel and shank piece 34 are coated with adhesive, such as rubber latex, and the parts are allowed 45 to set long enough to render the adhesive in proper condition for securing the parts together. Before the insole and the heel and shank piece are secured together, however, the opposite end portions of the shank stiffener 36 are inserted through the apertures 50 in the insole with the body portion 50 of the stiffener disposed at the upper side of the insole, and the shank stiffener is adjusted longitudinally to bring its forward end into a desired lengthwise relation to the insole. As indicated 60 in the drawing, the assembly of the shank stiffener with the insole imparts a longitudinal curvature to the insole which approximates that of the shank stiffener. Also, as indicated, the shank stiffener has struck up at its rear end a single 65 pointed spur or prong 70 which, during the molding of the insole 32 and the heel and shank piece 34, is forced into the material of the insole and thus functions positively to hold the shank stiffener against longitudinal displacement. The 70 heel and shank piece 34 is next laid with its coated surface upon the coated heel and shank portion of the insole and the edges of the parts are aligned by the use of any suitable gaging means.

The assembled parts are then subjected to 75 molding pressure which secures the heel and

shank piece to the insole and molds those parts so as to curve them both longitudinally and transversely to adapt them to conform to the longitudinal and transverse curvatures of the bottom of a last. Advantageously, the molding 5 may be effected by the use of molding forms which may be incorporated in a molding machine, such as that disclosed in my copending application Serial No. 701,814, filed December 11, 1933, upon which United States Letters Patent 10 No. 2,065,465 was granted December 22, 1936. After the parts have been secured together and molded the flap formed by the hereinbefore described channeling or edge slitting of the insole is raised and laid back into position to constitute 15 the lasting lip 38. Thereafter the opposite lateral edges along the shank portion of the unit are preferably reduced by the use of any suitable reducing means so as to provide the beveled surfaces indicated at 180 in Figs. 1 and 3, the angle 20 of bevel being such as to blend with the profile of the last.

Instead of securing the shank stiffener 36 in place by inserting its opposite end portions through apertures in the insole the shank stiffener 25 may be secured by means of tacks 186 to the reinforcing piece 340, as indicated in Fig. 5, or to the insole 320, as indicated in Fig. 7, the shank stiffener 360 being provided with the usual tack holes but having no attaching prong or spur. To 30 insure that the shank stiffener shall have no tendency to produce an undesirable ridge or bulge in the insole 320 and consequently in the outsole of the shoe a shallow groove 188 may be formed in the reinforcing member 340 to receive the 35 shank stiffener, as clearly indicated in Fig. 6.

Instead of forming a lasting lip integrally with the substance of the insole it may be desirable to secure a strip of tape or a plurality of strips of tape to the lower side of the insole to constitute 40 a lasting lip. As shown, for example, in Figs. 7 to 10, inclusive, strips of tape 52 may be secured by suitable fastening means, such as stitches 54, to the insole 320, the tapes being preferably 45 stitched to the insole before the reinforcing piece and the shank stiffener are assembled therewith. As indicated, the tapes may be stitched along their central median lines and later the portions of the tapes at opposite sides of the stitches raised by any suitable means, to 50 the positions indicated in Fig. 11, to provide an upstanding lasting lip. It is to be noted that inasmuch as the lips are initially stitched to the insole in a substantially flat condition they will not interfere with the operations of attaching 55 the reinforcing piece and molding the shank portions of the reinforcing piece and the insole. Moreover, by stitching the tapes to the insole before the reinforcing piece and the shank stiffener are assembled with the insole, those portions of 60 the tapes which are to constitute the lasting lips along the opposite lateral margins of the shank portion of the insole unit may be positioned much closer together inasmuch as it will not be necessary to confine the stitching to locations such as 65 to avoid the shank stiffener. In other words, there will be no shank stiffener present to interfere with the passage of the needle through the insole. This is of particular importance in the case of insole units having unusually narrow 70 shank portions where, as indicated in Fig. 10, the lines of tape-attaching stitches may necessarily have to be located so close together that the presence of a shank stiffener would interfere 75 with the stitching operation. Furthermore, it

is of course much easier to pass the stitches only through the insole than to pass them through both the insole and the reinforcing piece because of the thickness and toughness of the material (fiber, leatherboard or the like) of which the stiff reinforcing piece is composed.

The lasting lip 38 provides means to which a shoe upper may be stapled to hold it in place during the setting of the cement between the upper and the feather or margin of the insole, in accordance with the method of making cement-lasted shoes disclosed and claimed in United States Letters Patent No. 1,932,545, granted October 31, 1933, upon application of George Goddu. The particular lip formation herein shown, however, differs somewhat from that disclosed in the Letters Patent referred to.

It will be appreciated that it is practicable to form a lasting lip upon the insole in accordance with the methods herein described by reason of the fact that the reinforcing piece is to be secured to the upper or unlined side of the insole. Being ultimately disposed at the upper side of the insole the reinforcing piece cannot interfere with the securing of a satisfactory cement bond between the shoe upper and the insole unit. This will be readily appreciated in cases where the insole is composed of leather and the reinforcing piece of fiber, leatherboard or the like, inasmuch as it is well known that cement will adhere better to leather than to fiber or leatherboard. Moreover, if the insole is channeled so as to form a channel flap which is raised to provide a lasting lip as herein described, the portion of the feather or margin of the insole which is cut by the channeling knife is well adapted to receive cement in such a way as to insure the formation of a good bond between the upper and the insole. Furthermore, the shank stiffener, being also disposed at the upper side of the insole, does not reduce the area of the cementing surface in the shank portion of the shoe bottom as frequently happens when the shank stiffener is located at the lower or lasting side of the insole, particularly in the case of a narrow shank shoe.

Having described my invention, what I claim as new and desire to secure by Letters Patent of the United States is:

1. A shoe bottom unit comprising a lipped insole, a stiff reinforcing member for the heel and shank portions of the insole secured to the unlined side of the insole, and a narrow shank stiffener of substantially uniform width located throughout a portion of its length between the reinforcing member and the upper side of the insole and being exposed throughout another portion of its length at the lower side of the insole, the shank stiffener and the shank portions of

the insole and the reinforcing member being arched longitudinally to correspond to the longitudinal curvature of the shank portion of a last bottom and the shank portions of the insole and the reinforcing piece being also arched transversely.

2. A shoe bottom unit comprising a lipped insole having an aperture therein, a stiff heel and shank reinforcing piece secured by means of adhesive to the insole at the unlined side thereof, and a narrow shank stiffener strip located throughout the greater part of its length between the insole and said reinforcing piece but having a portion extending through said aperture and secured to the lipped side of the insole.

3. That improvement in methods of making shoe bottom units which consists in forming an insole having at one side a marginal flap lying substantially flat with respect to that side of the insole, securing to said insole at the opposite side thereof a shank stiffener and a shank reinforcing piece thereby providing a shoe bottom unit and molding said unit to curve said insole and said reinforcing piece longitudinally and transversely before placing the unit upon a last, and thereafter raising said flap into an upstanding position to constitute a lasting lip.

4. That improvement in methods of making shoe bottom units which consists in channeling an insole to provide a channel flap extending around the forepart and along both lateral marginal portions of the shank at one side of the insole, thereafter securing to the insole at the opposite side thereof a shank stiffener and a shank reinforcing piece to make a shoe bottom unit and molding said insole and said reinforcing piece to curve them both longitudinally and transversely in their shank portions before placing said unit upon a last, and finally raising said flap into an upstanding position to constitute a lasting lip.

5. That improvement in methods of making shoe bottom units which consists in securing a tape to one side of an insole thereby providing a lipped insole, and thereafter securing to the other side of the insole a shank stiffener and a shank reinforcing piece and molding the insole and the reinforcing piece.

6. That improvement in methods of making shoe bottom units which consists in stitching a tape in a substantially flat condition to one side of an insole, thereafter securing to the other side of the insole a shank stiffener and a heel and shank reinforcing piece and molding the shank portions of the insole and the reinforcing piece, and finally raising said tape into an upstanding position to serve as a lasting lip.

JOHN M. WHELTON.
